CLAIM

The ornamental design for a golf club cleaner, as shown and described.

DESCRIPTION

FIG. 1 is a front perspective view showing my new design; FIG. 2 is a front view thereof; FIG. 3 is a back view thereof; FIG. 4 is a left side view thereof; FIG. 5 is a right side view thereof; FIG. 6 is a top view thereof; FIG. 7 is a bottom view thereof; FIG. 8 is a left side perspective view thereof; and, FIG. 9 is a front perspective view thereof, the golf clubs shown in broken lines for use. The broken lines depict environmental structures and form no part of the claimed invention.
